UNITED STATES PATENT OFFICE.

OTTO CRONAU, OF NEW YORK, N. Y.

TOOL-HOLDER.

1,341,206.

Specification of Letters Patent.

Patented May 25, 1920.

Application filed July 29, 1919. Serial No. 314,076.

To all whom it may concern:

Be it known that I, OTTO CRONAU, a citizen of Germany, and a resident of the borough of Manhattan, city, county, and State 5 of New York, have invented certain new and useful Improvements in Tool-Holders, of which the following is a specification.

This invention relates to tool holders and has for its primary object to provide an improved mounting of the cutting bits in a double acting planer and shaper whereby the bits alternately engage and operate upon the work as the holder is moved in opposite directions.

15 It is a more particular object of my invention to provide a tool holder of the above character having pivotally mounted members in which the cutting bits are respectively secured, and a non-yielding positive 20 connection between said members whereby they are automatically oscillated in unison, and one of the cutting bits moved into operative engagement with the work as the other bit is moved out of such engagement, upon 25 a reversal of the rectilinear movement of the tool holder.

The invention further contemplates a very simple and compact arrangement of the several parts of my improved tool 30 holder, resulting in a strong and durable construction which is not liable to easily get out of order or require frequent repair.

Having the aforementioned objects in view, the present invention comprehends 35 certain novel and improved combinations of mechanical elements, and the structural characteristics thereof, as will be more fully developed in the following description and subsequently incorporated in the subjoined 40 claims.

In the accompanying drawing, wherein I have illustrated one practical embodiment of my invention and in which similar reference characters designate corresponding 45 parts throughout the several views,

Figure 1 is a side elevation of the tool holder, one side of the body being broken away;

Fig. 2 is an elevation at right angles to 50 Fig. 1; and

Fig. 3 is a detail fragmentary section of the work piece illustrating the cutting action of the tool bits.

Referring in detail to the drawing, 55 designates the body of the tool holder which

is in the form of a single metal casting having parallel side flanges 6. A rectangular shank 7 is formed integral with this body casting at one of its ends and is adapted to be suitably mounted in a carriage or other reciprocating part of the planer or shaping machine.

Between the parallel flanges 6, the tool bit carrying members 8 are arranged, said members being loosely mounted upon the shafts 9 for oscillatory movement, the ends of said shafts being fixed in the side flanges 6 of the body 5. Each of the members 8 is provided with an obliquely extending rectangular opening 10 to receive the shank 70 of a tool bit 11. These tool bits may be adjustably fixed in the openings 10 with their cutting points projecting the desired distance below the lower ends of the members 8 by means of the set screws 12 which are 75 threaded in bosses 13 formed upon the members 8.

At their upper ends and at the inner sides thereof, the members 8 are connected to each other by means of a rigid link bar 80 14, the ends of the link bar fitting loosely in slots or bifurcations formed in the respective tool carrying members 8 and being loosely engaged upon the transverse pivot pins 15 which are fixed in said members. 85 Each member 8 is further provided on its upper end with a shoulder 16 which is adapted to abut against the horizontal wall of the body 5 and thus limit the pivotal movement of said members in one direction. 90

In the operation of my improved tool holder as above described, during the movement of the holder to the right as seen in Fig. 1, the point of the left hand cutting bit 11 is engaged with the work piece W 95 and makes a "roughing cut" indicated at W' in Fig. 3 of the drawing. During this operation of the left hand cutting bit, it will be observed that the pressure of the bit upon the work piece tends to rock the member 8 in which the bit is mounted upon the pivot shaft 9, and hold the shoulder 16 thereof in close contact with the body 5. Through the medium of the link 14, the other of the members 8 is rocked upon its 100 shaft 9 and in a reverse direction to the movement of the member 8 first referred to, so that the other of the cutting bits 11 at the right will be held in an elevated position 105 and out of contact with the surface of the 110

work piece. When the reciprocating movement of the tool is reversed and pressure upon the point of the left hand cutting bit 11 is relieved, the member 8 in which the 5 bit is mounted oscillates upon its pivot shaft 9 and this bit is lifted from contact with the work piece while simultaneously, through the medium of the link 14, the right hand member 8 is rocked upon its pivot shaft and 10 the tool bit carried by said member is lowered into operative engagement with the work piece. This tool bit, as the holder is moved to the left, operates upon the rough cut surface previously formed and makes 15 a finished surface on the work piece as shown at W². These cutting or planing operations are repeated *ad infinitum* in the reciprocation of the tool holder until the entire surface of the work piece has been 20 operated upon and provided with a finished surface.

It will be apparent that my improved tool holder provides a double acting metal 25 planer or shaper which will be very positive and reliable in practical operation. No manual adjustments whatever are required, but the movement of the cutting bits from their active to inactive positions at the end 30 of each operating stroke of the holder occurs instantaneously and automatically. When one cutting bit is in action, the point of the other bit does not drag upon the surface of the work piece, but is supported entirely out of contact therewith. Thus wear 35 upon the bit points will be reduced to a minimum. The bit carrying members or blocks 8 are very compactly arranged and associated with the body of the tool holder and are operatively connected by means of 40 a single rigid link bar. I have therefore succeeded in producing a construction wherein springs or other easily breakable parts are dispensed with so that the device as a whole, will be durable and serviceable in practical use and not liable to get 45 out of order. It will be apparent of course, that the improved tool holder may be constructed in various sizes, and that the body of the holder as well as the bit carrying 50 blocks or members 8 may be otherwise shaped and proportioned than as indicated in the accompanying drawing.

In the preceding description and the accompanying drawing, I have disclosed one 55 practical embodiment of the invention, which, however, may likewise be exemplified in numerous alternative constructions. Accordingly the invention as herein claimed is to be considered as inclusive of all legitimate equivalents for the various elements 60 employed as well as other contemplated arrangements thereof, which may satisfactorily accomplish the desired results.

I claim:

65 1. A tool holder of the character de-

scribed, including a body, opposed oscillatable members mounted on said body and having their pivotal centers laterally spaced from each other, a cutting bit carried by each of said members, and a non-yieldable 70 connection between the bit carrying members to cause the unitary oscillation of said members and disengage one of the cutting bits from the work simultaneously with the engagement of the other cutting bit therewith when the reciprocating movement of the holder is reversed.

2. A tool holder of the character described, including a body, opposed oscillatable members mounted on said body, a cutting bit carried by each of said members, and a rigid link connection between the bit carrying members to cause the unitary oscillation of said members and disengage one of the cutting bits from the work simultaneously with the engagement of the other cutting bit therewith when the reciprocating movement of the holder is reversed.

3. A tool holder of the character described, including a body, opposed oscillatable members mounted on said body, a cutting bit carried by each of said members, and a single rigid link pivotally connected at its ends to said members in spaced relation to the pivotal centers thereof, between 90 the bit carrying members to cause the unitary oscillation of said members and disengage one of the cutting bits from the work simultaneously with the engagement of the other cutting bit therewith when the reciprocating movement of the holder is reversed.

4. A tool holder of the character described, including a body member having spaced side flanges, members pivotally mounted between said side flanges for oscillatory movement and longitudinally spaced from each other, a cutting bit carried by each of said members, and means disposed between the side flanges of the body member and connecting said bit carrying members to each other to cause simultaneous oscillation thereof and thereby disengage one cutting bit from the work and engage the other cutting bit therewith upon a reversal in the reciprocating movement of the tool holder.

5. A tool holder of the character described, including a body member having spaced side flanges, members pivotally mounted between said side flanges for oscillatory movement and longitudinally spaced from each other, a cutting bit carried by each of said members, and a single rigid link extending longitudinally between said side flanges of the body member and pivotally connected at its ends to the spaced bit carrying members to cause simultaneous oscillation thereof and thereby disengage one cutting bit from the work and engage the 130

- other cutting bit therewith upon a reversal in the reciprocating movement of the tool holder.
6. A holder of the character described including means for supporting spaced cutting bits converging with relation to each other toward the surface of the work, and automatic means for simultaneously shifting the cutting bits in relatively opposite directions to operatively engage one bit with the work and disengage the other bit from the work surface in the operation of the tool.
7. A tool holder of the character described including a body, opposed oscil-

latable members mounted on said body, a cutting bit carried by each of said members, said bits converging toward their cutting points, and means connecting said members to each other and operating to automatically transmit oscillating movement from one member to the other and thereby alternately engage the cutting bits with the work when the reciprocating movement of the holder is reversed.

In testimony that I claim the foregoing as my invention, I have signed my name hereunder.
